UNITED STATES PATENT OFFICE.

ALBERT MOEDE, OF REEDSVILLE, WISCONSIN.

ELEVATED CARRIER.

1,289,865.

Specification of Letters Patent. Patented Dec. 31, 1918.

Application filed March 6, 1917. Serial No. 152,801.

To all whom it may concern:

Be it known that I, ALBERT MOEDE, a citizen of the United States, and resident of Reedsville, in the county of Manitowoc and 5 State of Wisconsin, have invented certain new and useful Improvements in Elevated Carriers, of which the following is a specification.

This invention relates to elevated carriers 10 and has more especial reference to an improved hay carrier.

The invention has for its dominant object to provide an elevated carrier adapted for use in barns, stables and like buildings, 15 whereby, hay and other matter can be moved thereupon to the desired point and then discharged or dumped from the same.

Another object of the invention is to provide a novel arrangement of tracks, where- 20 by the carrier may be moved longitudinally or transversely of the building in which it is placed without the tilting of the load, thus facilitating the moving of the loads to the desired point before dumping the same 25 therefrom.

Among other aims and objects of the invention may be recited, the provision of a device of the character mentioned with a view to compactness, and in which the number 30 of parts are comparatively few, the construction simple, the cost of production small, and efficiency and operation high.

Another important feature of the invention resides in the provision of tripping 35 means for the carrier, rendering it possible to dump the same with but little effort, irrespective of the weight of the load thereon and then allowing the same to be automatically returned to normal position.

The invention consists, furthermore, in the novel arrangements and combinations of the parts of the device, as well as in the details of the construction of the same, all of 40 which will be more fully described in the following specification and then finally embodied in the clauses of the claim, which are 45 appended to the specification and which form an essential part of the same.

The invention is clearly illustrated in the 50 accompanying drawings, in which:

Figure 1 is a side elevation of my improved elevated carrier as applied to a fragment of a building frame;

Fig. 2 is a transverse section through the 55 traversing track therefor;

Fig. 3 is an end elevation of the carrier;

Fig. 4 is a transverse section there-
through;

Fig. 5 is a fragmentary detail in perspective of one of the platform tripping elements 60 of the carrier;

Fig. 6 is a fragmentary detail in top plan thereof; and

Fig. 7 is a detail in perspective showing the arrangement of the rope for moving the 65 carrier longitudinally of the track;

Fig. 8 illustrates brake mechanism used to control the carrier.

Similar characters of reference are employed in all of the above described views to 70 indicate corresponding parts.

Referring now more specifically to the several figures of the said drawings, it is to be noted that I have shown by way of illustration the improved elevated carrier as applied to the studding or framing of a barn or like building, the framing comprising horizontal and vertical members and being designated in its entirety by the numeral 1. The upper portions of the framing 1 are inclined whereby the same may serve as means 75 for efficiently supporting the roofing of the building.

With more especial reference to the present improvements, there are provided end 80 pieces 2 which are secured to certain of the horizontal members of the framing 1 at points in proximity of the end pieces of the said framing and have their side portions arranged diagonally to permit the same to 85 conform to the roof of the building when applied. A pair of these end pieces 2 are secured to the opposite extremities of the framing 1 and have fastened thereto by means of brackets generally designated 3, 90 tracks 4, which tracks are of a shape complementary thereto. The tracks 4 may be and preferably are formed of metal and have their lower extremities secured to the adjacent horizontal members of the frame 1 to 95 prevent undue lateral or vertical movement thereof.

Carriages are provided comprising cross bars 5 formed of hingedly connected sections and having bifurcated extremities whereby 100 trucks 6 may be connected thereto through the medium of bolts 7, the upper extremities of the bolts being pivotally connected to the said trucks. As will be understood, the wheels of the several trucks are 105 adapted to be arranged upon the transversely disposed tracks 4 and are adapted

to move therealong for a purpose which will be subsequently apparent. Pulleys 8 are supported upon depending brackets 9 which have the upper ends thereof secured to the tracks 4 and receive thereover flexible connections 10, certain of the extremities of which are connected to the bifurcated extremities of the cross bars 5 as at 11 while the remaining ends pass downwardly from 5 each of the ends of the cross bars and about 10 weighted double pulleys 12 and thence upwardly over the same about pulleys 13 secured to certain of the horizontal members of the framing 1. As shown in the Fig. 1, 15 certain of the flexible connections 10 extend from their respective trucks longitudinally of the framing 1 over pulleys 14 mounted on each side of the frame 1 to points in proximity of the connection arranged upon 20 the trucks positioned at the opposite end of the framing. By this arrangement, the several connections may be conveniently operated by the user while standing in one position, the weighted double pulleys 12 serving 25 as means for normally maintaining the same taut and as a consequence, obviating the tangling and other disarrangements of the connections.

Depending arms 15 are pivotally secured 30 to the intermediate sections of the cross bars 5 as at 16 and support in suitable brackets 17 a single longitudinally disposed beam 18, the beam serving as a track for permitting longitudinal movement of the carrier, 35 which will be more fully hereinafter described. Angle irons 19 are arranged over the various corners of the beam 18, thus, serving as wear compensating means therefor and affording an even and uniform bearing surface for the truck of the carrier, at all 40 times. It is to be understood, that by pivotally connecting the beam 18 with the several cross bars 5, through the medium of the arm 15, the carriages as arranged upon 45 the transversely disposed track 4 may be moved over the inclined side portions thereof without the tilting of the same.

A carrier indicated in its entirety by the numeral 20 is provided and includes a truck 50 formed of a squared framing 21, the framing being of a size to snugly engage over the beam 18 and has journaled in the top, bottom and side portions thereof a plurality of rollers 22, the said rollers being so arranged 55 as to bear upon the various portions of the angle irons 19. Laterally projecting arms 23 are secured to the opposite side portions of the squared frame 21 and have their outer extremities rigidly connected by longitudinally arranged bars 24. Intermediate the 60 ends of the bars 24, metal platforms 25 having downturned outer extremities are secured, while upon the upper faces of the bars, arms 26 are pivotally mounted as at 65 27 and are normally maintained in position

thereover by means of coiled springs 28, certain of the ends of which are connected to brackets 29 engaged with the bars 26 while the remaining extremities are connected to other longitudinally disposed bars 70 30 also arranged upon the arm 23 in spaced relation from the bars 24. A platform 31 having end pieces is pivotally secured to the upper portion of the squared frame 21 by securing to the under face thereof at a point intermediate its sides depending arms 32 and passing through the arms, pivot bolts 33 mounted in suitable bearings upon the said upper portions of the frame 21. Coiled springs 34 are secured to the apertured 75 lower extremities of the several arms 32 and have their remaining ends affixed to pieces or uprights 35 mounted upon the longitudinally disposed bars 30. Other coil springs 36 are connected to the pivotal uprights 35 80 and extend into engagement with the bars 24. Thus, it is evident that the tension upon the opposite sides of the arms 32 will be equalized and as a consequence, the platform 31 will be permitted to remain in a substantially horizontal position when not loaded. Legs 37 are pivotally secured in brackets 38 affixed to the under face of the platform 31 at points adjacent the opposite side portions thereof and carry upon their 85 lower extremities rollers 39, which rollers are adapted to be normally arranged upon the several platforms 25 secured to the longitudinally disposed bars 24. To maintain the legs 37 in position wherat the rollers 39 90 thereof will at all times engage the platforms 25 when the platform 31 of the carrier is in horizontal position, rods 40 are pivotally connected to the same and extend through apertured brackets affixed to bars 95 41 carried upon the under face of the platform 31. About portions of the rods 40, coiled springs 42 are arranged and have their opposite extremities so engaged as to maintain their respective legs 37 in the desired 100 position. Cables 43 and 44 have certain of their ends connected to immovable parts of the frame 21 and extend over pulleys indicated in general by the numeral 45 105 certain of which are connected to the arms 26 while the others are carried by the carrier, said cable then being passed longitudinally of the framing 1 to points in proximity of the free ends of the cables 110 whereat they may be conveniently reached 115 by the user. Obviously, by pulling the cable 44, the pivotal arm 26 as engaged thereby will be moved inwardly into engagement with the legs 37 as adjacent the same, forcing the same from its respective platform 25 and allowing the platform 31 of the carrier, which is loaded, to be tilted to that side in order that its load may be dumped therefrom. When the load has been removed 120 from the platform of the carrier, the same 125

130

will immediately return to its normal or horizontal position, due to the engagement of the coiled springs 34 and 36 with the opposite side portions of the several arms 32. 5 To tilt the opposite side of the platform, the cable 43 is of course pulled to cause the disengaging of its respective leg portion 37 from the adjacent platform 25. The rods 40 will permit pivotal movement of the several legs 37 against the tension of the spring carried thereby, but will force the legs immediately to their normal positions when the same are released, thereby, allowing the legs to properly reengage the several platforms 25 when the load is discharged from the platform of the carrier.

To move the carrier 20 longitudinally of the frame 1, cables 46 and 47 are engaged with the oppositely disposed portions of the carrier truck and extend over pulleys 48 secured to portions of the framing, whereupon the said cables are extended downwardly and about a weighted double pulley 49, similar to the pulley 12 and upwardly 25 into engagement with a fixed element 50 as secured to a portion of the said framing. By this means, the cables will be maintained taut at all times.

Brake bars 51 are slidably arranged in slots formed in the framing 21 and are adapted to bear upon the rollers 22 at the opposite ends thereof. A coiled spring is engaged with one of the brake bars and the adjacent portion of the framing for normally maintaining the bars in disengaged 35 positions, while the brake bars are connected with a cable 52 extending over a pulley 53 mounted on the remaining end of the framing whereby the brake bars may be engaged 40 with their respective rollers when desired.

From the foregoing, it will be understood by workers in the art, that I have provided an elevated carrier which, by reason of its construction and mounting may be moved to 45 any desired point within the building in which it is arranged and then dumped to discharge its load therefrom with but little effort upon the part of the operator or user. The device may be advantageously used in 50 the husbanding of live stock, whereby feed, such as hay or the like, may be conveyed and deposited in the various stalls of the stock. Further, the device may be also used as means for removing various debris from 55 the building during the cleaning of the same or various parts thereof, thus, affording an efficient loading and unloading device.

I am aware that changes may be made in the various arrangements and combinations 60 of parts as well as in the details of the construction of the same, without departing from the scope of my present invention, as defined in the appended claims. Hence, I do not limit the invention to the exact arrangement and combinations of the device

and parts, as illustrated in the accompanying drawings, and as described in the accompanying specification, nor do I confine myself to the exact details of the construction of the said parts.

70

I claim:

1. A device of the character described, in combination with a transversely movable track therefor, a carrier movable over said track, said carrier including a truck having 75 a platform pivotally connected thereto, other platforms carried by the truck, pivotal legs engaged with said first platform and engageable with said second platforms, and means engageable with the pivotal legs 80 for moving the same selectively from said second platforms to cause dumping of the first platform.

2. A device of the character described, in combination with a transversely movable 85 track therefor, a carrier movable over said track, said carrier including a truck and a platform pivotally connected thereto, other platforms carried by the truck, pivotal arms arranged adjacent said second platforms, legs pivotally secured to the opposite sides of the first platform and engageable with said second platforms, and means connected to said pivotal arms and extending to points distant therefrom for moving the 95 same into engagement with said legs, as and for the purpose set forth.

3. A device of the character described, in combination with a traversing track therefor, a carrier movable over said track, said 100 carrier including a truck and a platform pivotally connected thereto, other platforms carried laterally of the truck, pivotal arms arranged adjacent said second platforms, legs pivotally engaged with the 105 opposite sides of the first platform and engageable with said second platforms, spring means engaged with the first platform and said legs for normally maintaining the same in engagement with said second platforms, other spring means connected to the truck and extending into engagement with the first platform for maintaining the same in normal position, and means connected to the pivotal arms and extending to a point 110 distant therefrom for moving the same into engagement with the adjacent legs, as and for the purpose set forth.

4. In a device of the character described, in combination with a traversing track 115 therefor, a carrier movable over said track, said carrier including a truck having a squared frame engageable over the track, a platform pivotally connected to the truck, spring means engaged with the truck and the platform for normally maintaining the same in horizontal position, other platforms carried by the truck laterally thereof, pivotal arms arranged in proximity of said second platforms, a plurality of legs piv- 120

125

130

totally secured to the opposite sides of said first platform and engageable with said second platforms, spring means engaged with the legs for maintaining the same in their normal positions, and means connected to the pivotal arm for moving the same into engagement with the adjacent legs, as and for the purpose set forth.

5. A device of the character described, including spaced apart transversely disposed tracks having inclined side portions, a plurality of carriages movable on said tracks, hinged cross bars engageable with certain of said carriages, means connected to the 10 cross bars for imparting movement to their respective carriages, a depending arm pivotally secured to the cross bars, a longitudinally disposed beam carried by said arm, and a carrier movable over the longitudinally disposed beam.

15. A device of the character described, including spaced apart transversely disposed tracks having inclined extremities, carriages movable over said tracks, hinged cross bars connected to certain of the carriages, means engaged with the cross bars for imparting movement to their respective carriages, depending arms pivotally secured

to the cross bars, a longitudinally disposed beam carried by said arms, a carrier movable over said beam, said carrier including a truck having a squared frame engageable about the beam, a platform pivotally connected to the truck, other platforms carried laterally of the truck, pivotal arms arranged adjacent said second platforms, a plurality of legs pivotally secured to the opposite sides of said first platforms and engageable with the second platforms, spring means engaged with the legs for maintaining the same in their normal positions, means connected to the pivotal arms for moving the same into engagement with the legs for disengaging them from the second platforms, spring means connected to the front and to the opposite sides of the first platforms for normally maintaining the same in horizontal position, and other spring means engaged with the truck and certain of the ends of said pivotal arms for maintaining the same in their normal positions.

20. In testimony whereof, I affix my signature hereto.

ALBERT MOEDE.
